JAMES H. SKITT, OF PHILADELPHIA, PENNSYLVANIA, ASSIGNOR TO SMITH, DRUM & COMPANY, OF PHILADELPHIA, PENNSYLVANIA, A CORPORATION OF PENNSYLVANIA

DYEING APPARATUS

Application filed January 21, 1930. Serial No. 422,296.

The present invention relates to the art of dyeing and more particularly to a means for supplying a liquor to a material to be dyed or otherwise treated.

In dyeing apparatus heretofore employed in treating and dyeing materials, particularly skeins of yarn, it has been customary to suspend the skeins upon a perforated hollow rod and discharge the dyeing liquor through the rod perforations with sufficient pressure to lift the skeins and bring about what may be termed a floating action in that the discharged liquor holds the yarn away from the rod. While this floating action is 15 advantageous in promoting uniform treatment by the liquor it is unfortunately accompanied by a forcing apart of the skein threads (due to the full pressure of the discharging liquor acting directly on the under surface 20 of the skein, so that much of the dye liquor passes through the skeins and falls in a spray at some distance away from the skeins). Thus the suspended outside portions of the skeins are exposed to the air and oxidation 25 takes place leaving the yarn streaky and discolored instead of uniformly dyed.

Some of the objects of the present invention are to provide an improved apparatus for dyeing or otherwise treating materials; 30 to provide a mechanism for supplying a liquor to yarn skeins or other goods wherein the liquor is uniformly distributed to the goods being treated; to provide a dyeing or treating apparatus wherein the liquor is so applied as to prevent air from coming in 35 contact with the material during the treating process; to provide means for supplying a dyeing or treating liquor to skeins of yarn in such a manner as to prevent displacement 40 and entanglement of the skein strands; to supply a liquor to suspended yarn skeins in such a manner as to virtually enclose the skeins in a film of the liquor during the dyeing or treating operation; to provide an apparatus for supplying a liquor for dyeing and treating purposes wherein the discharged liquor is baffled and controlled 45 to exit against the yarn as an uninterrupted stream entering and travelling through the skein strands to fall back as a film sheet flow-

ing down the exposed side of the hanging skeins; to provide an apparatus for preventing loss of liquor due to the spraying action of a perforated tube; and to provide other improvements as will hereinafter appear.

In the accompanying drawings, Fig. 1 represents a side elevation of a carrier for yarn or other material and embodying one form of the present invention; Fig. 2 represents a perspective of the same, broken away to more 55 clearly illustrate the internal construction; Fig. 3 represents a section on line 3-3 of Fig. 1; Fig. 4 represents a perspective of a modified form of carrier; Fig. 5 represents a section on line 4-4 of Fig. 4 showing a 60 skein of yarn in place; and Fig. 6 represents a detail of one of the spacer elements.

Referring to the drawings one form of the present invention consists of a carrier 10 arranged to be supported at one end upon 70 a liquid supply pipe 11, which is carried by the frame 12 of the dyeing or treating machine to which the invention is applied. Preferably the support for the carrier 10 is located at one end thereof in order to leave 75 the opposite end free and unobstructed so that skeins of yarn or other material can be readily placed thereon to be held in suspended position. In the present instance, by way of example, the material shown is in the form 80 of skeins of yarn 13 and may be any grade of material since the carrier, here shown operating in conjunction with the dyeing or treating liquid, functions efficiently for fine grades, such as silks and rayons, as well as 85 the coarser grades of material. It will be understood that the invention is also intended for use in the treating of piece goods or any other material which can be supported 90 thereon.

In the present instance the carrier 10 consists of an elongated tube 14, preferably of substantially cylindrical shape but having its top portion split longitudinally to provide a slot 15 opening outward so that liquid discharged from the inside of the tube 14 can have unobstructed contact with the underneath portion of any material supported above the tube 14. The two ends of the split portion are bent inwardly and reversely 95 100

turned to form baffles 16 respectively at the sides of the slot, which baffles project into the path of the supplied liquid as will presently appear.

- 5 For the purpose of discharging the treating liquid into the tube 14 another element of the carrier 10 consists of a hollow support 17, here shown as of rectangular section and having a length equal to the length of the 10 tube 14. This support 17 is fixedly mounted within the tube 14 being arranged diametrically thereof and extending axially of the slot 15 though its sides are respectively spaced from the baffles 16 in order that the 15 discharged liquid can pass out of the tube 14 through two relatively narrow passages. The height of the support 17 is somewhat greater than the diameter of the tube 14 so that the skeins of yarn are mainly supported 20 in spaced relation to the side outlet passages, but the side portions of each skein rest upon and generally follow the contour of the tube 14.

The supported end of the hollow support 25 17 is connected to the inlet pipe 11 so that the dyeing or treating liquid enters the support 17 and is discharged therefrom by way of a plurality of holes 18 provided in the two sides of the support 17. These rows of holes 30 are preferably in close proximity to the bottom of the tube 14 and since the inlet pipe 11 enters the support 17 at substantially the center portion of the tube 14, the entering liquid is required to pass downwardly in the 35 support 17 and then exit laterally against the upwardly and curving walls of the tube 14. As the entering liquid is under pressure from the supply pump the streams of liquid leaving the two rows of holes 18 follow upward along the respective inner faces of the 40 tube 14 and respectively strike the baffles 16. In this way the direct force of the liquid is broken and the liquid passing around the baffles rises through the side passages of the 45 slot 15 into contact with the undersurface of the supported skeins of yarn. While the pressure of the liquid has thus been reduced sufficiently to prevent separation of the skein strands, the flow through the passages has 50 enough pressure for the liquid to work upwardly through the skein strands and flow from the top surface thereof down over the sides of the hanging strands. While this flow upward and outward of the slot passages takes place under pressure, it is not 55 the pressure of direct impact and therefore floats, fills and covers the yarn without causing displacement and tangling of the strands. By reference to Fig. 3 of the drawings it 60 will be seen that the two streams of discharging liquid leave the tube outwardly divergent with respect to the support 17 and this brings about the very desirable result of covering the outer exposed sides of the skeins with a 65 film 24 which in effect insulates them from

contact with the air. In addition to this formation of a film upon the outer sides of the yarn, there is a like film 25 formed upon the inner sides of the yarn due to the fact that the emerging liquid rolls downwardly 70 between the skeins and the face of the tube 14 as will be seen. The aforesaid diverging action of the liquid as it is discharged from the tube 14 is made more effective by the fact that the support 17 projects above the top 75 of the tube 14 and thus provides two ejecting passages 20 extending lengthwise of each side of the tube, each of which increases from its junction with the slot 15.

The ends of the carrier 10 are respectively 80 closed by caps 21 and 22, the former sealing the free end of the carrier while the latter is apertured to allow the passage of the liquid supply pipe 11. Each of these caps is provided with a circumferential flange 23 which 85 serves to prevent endwise displacement of the supported skeins of yarn.

In the form of the invention shown in Figs. 4, 5 and 6 a support for the skeins is provided in the form of a blade 26 which extends 90 medially of the slot 27 of the tube 28 between the baffles 30 formed by the reversely turned ends of the tube 28. The blade 26 is welded or otherwise fastened to the top of a pipe 31 which runs lengthwise in close proximity to 95 the bottom of the tube 28 and is in communication with the source of liquid supply, such as the inlet pipe 11 of Fig. 1. Two rows of discharge outlets 32 are provided respectively in the sides of the pipe 31 and in such relation to the inner wall of the tube 28 as to direct the streams of liquid against this wall to rise upwardly and be deflected by the baffles 30.

For subdividing the two streams of liquor leaving the tube 28 by way of the two longitudinal passages, two strips 33 of suitable material are mounted to divide each stream into two streams leaving opposite sides of the blade 26. These strips 33 are held in place 105 edgewise and radially of the carrier by a plurality of arc shaped spacers 34 which seat upon the pipe 31 and have radially disposed slots 35 to receive the respective strips 33 and a centrally arranged slot 36 to interfit with the blade 26. Thus with the spacers held by the blade 26 a simple and effective anchoring 110 of the spacers is obtained and the strips 33 are properly disposed in radial spaced relation. As a result the liquor wells up through the main outlet passages and is so subdivided 115 as to provide streams passing respectively upwardly through the skein strands and laterally outwardly therethrough to produce the desired film action.

In the operation of the carrier the skeins of 120 yarn 13 are passed over the free end of the carrier 10, and placed upon the support 17 side by side until the carrier is filled with the skein between the end flanges 23. In this 125 130

position the sides of the skeins rest upon the sides of the tube 14 and the lower ends of the skeins hang well below the carrier 10 and generally over a tank containing the dyeing or treating liquid. With the skeins so positioned the pump or other means of supplying liquid to the carrier 10 is started and the fluid enters the support 17 at substantially the central portion thereof and exits through the side holes 18 with a pressure which causes the fluid to discharge upwardly along the sides of the tube 14, impact with the baffles 16 and then pass around the baffles and exit through the two side passages 20, where it enters the underside of the skeins, forces its way therethrough, so that some of the liquid runs down the outside of the skein, another portion traverses the skein strands and still another portion travels along the inner face of the skein. That portion of the liquid which flows from the outside of the skeins is sufficient in quantity to form a continuous film 24 which is maintained throughout the length of the skeins, while the portion that flows along the inner sides of the skein forms a like film 25, also extending throughout the length of the skein. These two films form an important feature of the invention in that each serves to prevent air from coming into direct contact with the skein strands during the dyeing operation and hence discoloration and uneven dyeing is prevented because it is impossible for the disadvantageous oxidation to occur.

While the foregoing has dealt with several forms of apparatus embodying the present invention, it is here pointed out that fundamentally the invention embodies a new method of dyeing which can be carried out by other forms of apparatus other than that here illustrated. Thus broadly stated the method consists in causing a surplus of dyeing or treating liquid to flow between yarn skeins and the support thereof under such a pressure as to lift the skeins slightly from the support to give a flooding of the skein threads with an accompanying flow of the liquid along the inner and outer faces of the skeins in the form of a film which protects the skeins from contact with the air during the dyeing step. The flooding action is caused by the welling of the liquid upwardly through the discharge passages, but the floating action is not sufficient to cause lateral displacement of the skeins or the skein threads.

Having thus described my application I claim:

1. A carrier for supporting material to be treated comprising a tube provided with a longitudinal slot, a hollow support in said tube entering said slot to provide two liquid discharge passages leading from said tube, said support having discharge holes in the sides thereof, and means for introducing liquid into said support.

2. A carrier for supporting material to be treated comprising a tube provided with a longitudinal slot, a hollow support in said tube entering said slot to provide two liquid discharge passages leading from said tube, 70 said support having discharge holes in the sides thereof, baffles respectively between said passages and said holes, and means for introducing liquid into said support.

3. A carrier for supporting material to be treated comprising a tube provided with a slot, a tubular member having a part entering said slot to form a support for material, said member having discharge holes in the sides thereof, means for introducing liquid 80 into said tubular member, and means for subdividing said slot into a plurality of discharge passages.

4. A carrier for supporting material to be treated comprising a tube provided with a slot, a tubular member having a part entering said slot to form a support for material, said member having discharge holes in the sides thereof, and strips respectively supported between said parts and said tube to 85 form a plurality of discharge passages.

5. A carrier comprising a tubular support for material to be treated provided with a liquid discharge slot in the top portion thereof, a supplemental support for holding a portion of said material spaced from said tubular support, and means to supply liquid to said tubular support to discharge through said slot into the space formed between the material and the tubular support. 100

6. A carrier for supporting material to be treated comprising a tube provided with a slot, a support entering said slot to form a liquid discharge passage leading from said tube, and means to introduce liquid into said tube to discharge through said discharge passage. 105
